UNITED STATES PATENT OFFICE.

JOHN E. CARRUTHERS, OF AUBURN, MAINE, ASSIGNOR OF ONE-HALF TO WILLIAM A. PAUL, OF AUBURN, MAINE.

BUILDING-ELEVATOR.

1,299,124.

Specification of Letters Patent.

Patented Apr. 1, 1919.

Application filed February 1, 1919. Serial No. 274,504.

To all whom it may concern:

Be it known that I, JOHN E. CARRUTHERS, a citizen of the United States, residing at Auburn, in the county of Androscoggin and 5 State of Maine, have invented certain new and useful Improvements in Building-Elevators, of which the following is a specification.

My invention relates to improvements in 10 elevators and more particularly to freight elevators in buildings. Its objects, among others, are to provide means whereby the elevator in rising and falling opens automatically the trap doors at the floors of the 15 building and the entrance gate or gates to the elevator.

In the accompanying drawings, Figure 1 is a side view with some parts broken away 20 of an elevator well and elevator with my improvements applied thereto; Fig. 2 is a front view of the same with parts broken away and Fig. 3 is a horizontal sectional view taken on line α — α Fig. 1.

The same reference characters indicate 25 like parts in the several figures.

In the drawings, the elevator is shown in the position where the trap doors are open and the condition will be the same at any floor whether the elevator be rising or falling. 30 In said drawings, 1 is the elevator well, 2 the building frame. These may be of any convenient construction and arrangement. The elevator is adapted to be raised or lowered by power and in any convenient manner. 35 As shown, the power is applied to a cable 3 passing over a pulley 4 on the building frame, the cable 3 being secured to the top of the elevator. The elevator consists of a platform 5 and supporting frame 6, the 40 top of the frame comprising a rectangular band 7. To the bottom of the elevator are attached outwardly extending wedge-shaped door openers 8 and, at the top of the frame, are attached similar wedge-shaped door 45 openers 9. In the floor between two rooms, are provided ways 10 in which are positioned horizontally movable trap doors 11 adapted, when brought together, to close the 50 floor opening in the well. These doors on the adjacent edges and on each side are preferably provided with anti-friction rolls 12 positioned so that, when the elevator descends or ascends, the wedge-shaped door openers 8 and 9 engage the anti-friction rolls 12 and

force the doors apart to permit the elevator 55 to pass from floor to floor.

In the elevator well frame on the entrance side are vertical grooved ways 13 in which is loosely mounted a vertically reciprocating gate 14. This gate may be of any convenient 60 style and its vertical edges extend into and reciprocate in said grooved ways, the width of the gate being less than the space between the bottoms of the two grooves, thus running loosely in the ways. The gate is raised by 65 a cable or belt connection 15 between it and the trap doors. This cable 15 passes over a pulley 16 at the top and attached to the top of the frame by a staple 17 or in any convenient way. The cable then passes down 70 preferably in the grooved ways 13 in which the vertical door reciprocates, thence rearwardly around a stationary truck 18, thence around a truck 19 attached to the inner door, thence back and attached to the edge of the 75 other door at 20. It is noted that the two sides of the elevator door and well and operating mechanism are substantially duplicates. Thus, it will be seen that, when the wedge 8 or 9 forces the sliding doors apart, 80 the action of the cable is to raise the vertical reciprocating door. Now, when the elevator passes above or below the floor, the weight of the reciprocating door is sufficient to return the trap doors together, thus, closing 85 the trap opening in the well as soon as the elevator has passed in either direction. The trap doors are mounted on trucks 22 which travel on a track 21. The reciprocating door is provided at the top with a buffer 23 90 mounted on rods 24 on the top of the frame and having coil springs 25 upon said rods between the buffer and the top of the door frame. The frame of the elevator and the frame of the well are provided with a tongue 95 and groove structure 26 for guiding and steadyng the movement of the elevator in the well.

I claim:

1. In a device of the character described, 100 an elevator well, a vertically movable gate, horizontally movable trap doors, a cable connecting said gate and doors and an elevator provided with wedge-shaped trap door openers.

2. In a device of the character described, 105 an elevator well, a vertically movable gate, horizontally movable trap doors provided

with anti-friction rolls in their adjacent edges, a cable connecting said gate and doors and an elevator provided with wedge-shaped door openers.

5. In a device of the character described, an elevator well, vertically grooved ways in the frame adjacent said well, a vertical gate free to move in said ways, horizontally movable trap doors, cables connecting said gate and doors and an elevator provided with wedge-shaped trap door openers.

4. In a device of the character described, an elevator well, a vertically movable gate, horizontally movable trap doors provided with anti-friction rolls in their adjacent edges, a cable connecting said gate and doors and an elevator provided with wedge-shaped trap door openers adapted to engage said anti-friction rolls and open said doors, the weight of the gate being sufficient to overcome the inertia of the trap doors and close them after the elevator has passed.

5. In a device of the character described,

an elevator well, a vertically movable gate, horizontally movable trap doors, provided with anti-friction rolls in their adjacent edges, a cable connecting said gate and trap doors and an elevator provided on the top and bottom with wedge-shaped trap door openers, the opening of the trap doors raising the gate and the weight of the gate closing the trap doors after the elevator has passed.

6. In a device of the character described, an elevator well, a vertically movable gate, horizontally movable trap doors, a cable connecting said gate and doors on each side, one end of the cable being attached to the gate, an anti-friction roll carried by the remote trap door over which said cable travels and the other end of the cable attached to the other trap door whereby the rising or falling of the elevator raises the gate.

In testimony whereof I affix my signature.

JOHN E. CARRUTHERS.
